SHEET ATTACHING MECHANISM

Walter W. Guyon, Rochester, N. Y.

Application May 25, 1944, Serial No. 537,246

6 Claims. (Cl. 1-3)

1

This invention relates to a sheet attaching mechanism, applicable more particularly to stapling machines of conventional form embodying a relatively movable anvil and head for securing a staple through a plurality of sheets, and it has for its purpose to provide a construction that will enable attaching two or more sheets together by fastening a staple around one corner of the sheets and extending from around one edge across the corner of the outer sheet, around the adjacent edge, and back on the opposite outer surface, thus holding the sheets together by frictional engagement between the sheets and the staple, which occupies only the extreme corner portion of the sheets.

The usual practice in stapling a multiplicity of paper or other sheets together is to attach the staple parallel to and spaced from one edge, and where the staple is attached at one corner, it penetrates the sheets and is frequently located a substantial distance from the edges so that if it later becomes necessary to separate the sheets, the staple must first be removed by bending back its ends with a suitable instrument, or else the sheets must be defaced by tearing them apart, and one object of the invention is to afford a structure that enables fastening together a multiplicity of sheets by means of a staple located at the extreme corner of the sheets so that the staple can be easily and quickly removed with the fingers by exerting the tension required to overcome the frictional engagement between the staple and the adjacent surfaces of the sheets, a sheet can be torn off along the line of the staple by destroying only a small corner portion of the sheet, or a sheet can be pulled out from the rest without destroying or seriously defacing it.

The invention makes it possible to use staples as temporary or frictional retaining devices for holding together a multiplicity of sheets and thus to take the place of the conventional paper clips or other similar fastening elements and effect a considerable saving in cost, while affording instrumentalities which hold a multiplicity of sheets together with sufficient tightness to function satisfactorily as a permanent fastener, but permitting easy removal of the fastener or separation of one or more sheets when desirable.

Another purpose of the invention is to afford a structure that can readily be applied to a conventional stapling machine without requiring redesign of the stapling feeding and operating mechanism.

To these and other ends, the invention consists in the construction and arrangement of parts

2

that will appear clearly from the following description when read in conjunction with the accompanying drawing, the novel features being pointed out in the claims following the specification.

5 In the drawing:

Fig. 1 is a view in side elevation showing the application of a preferred embodiment of the invention to a stapling machine of known form;

10 Fig. 2 is a plan view of the base of the machine, partially broken away;

Fig. 3 is a bottom plan view of the stapling machine head with the plunger in section, showing a modified form of the invention;

15 Fig. 4 is a side elevation of the construction illustrated in Fig. 3;

Fig. 5 is a plan view of a stapling machine base, showing a further modification;

20 Fig. 6 is a plan view showing the application of a staple to a series of sheets;

Fig. 7 is a similar view showing the staple applied in a somewhat different manner, penetrating slightly the edges of the sheets, and

25 Fig. 8 is a similar view showing the application of the invention in fastening a sheet to the surface of a larger sheet.

The invention is useful and of particular advantage wherever it is desirable to attach together two or more sheets of paper or other material and hold them in any attached relation as long as desired, while permitting quick removal of the fastening means if necessary or the removal of a sheet by tearing it at the corner along the staple where attached, or by removing it 35 against the frictional resistance of the staple, and instances of such uses are found in attaching a check, price list, folder, return card, or other sheet to a remittance blank, statement, letter, or advertising broadside respectively, also the fastening of a smaller sheet on to a larger sheet in spaced relation to its edges as in affixing merchandise on display boards, and while the invention is susceptible of use with conventional staples of standard size, it is preferable to employ

40 a somewhat longer staple, for instance about three-quarters of an inch or more in length, so that when the staple is fastened across the corner portions of a plurality of sheets and extends

45 around the adjacent edges in frictional engagement with the exposed surfaces of the outer sheets, the fastener is of sufficient length to engage a considerable portion of the surfaces of the sheets and thus hold the sheets together frictionally with such pressure as to prevent their 50 55

accidental separation or displacement and to afford a practically permanent attachment.

The invention in one preferred embodiment, as illustrated in Figs. 1 and 2, is shown as applied to a conventional type of stapling machine including a base 1, anvil 2 having the usual staple recess 3, while 4 designates the pivotally mounted head provided with a plunger 5 that is operable to force a staple through the staple channel 6 into the staple recess 3 of the anvil.

In order to position the sheets on the anvil in the required relationship to the staple recess and staple, so that the latter will extend across the corner portions of the sheets and around the adjacent edges, there is provided positioning means which may be in the form of lines, pins, or other indicating devices or abutments, and here shown as straight flanges or guides 7 formed integrally with or otherwise attached to the base 1 and preferably located symmetrically on opposite sides of the longitudinal center of the staple recess 3.

The guides 7 are located along lines at right angles to each other and inclined to the staple recess in such relation to the staple recess 3 that when a sheet is inserted cornerwise over the staple recess and its adjacent edges are in contact with the guides 7, said edges will coincide approximately with the ends of the staple recess 3 or be located slightly beyond the ends of the recess. Thus when the staple is fastened, it will extend entirely around the edges of the sheets, as in Fig. 6, or it may penetrate the edges slightly and extend through pockets or notches thus formed in the edges by the staple, as in Fig. 7, to give a slightly tighter attachment between the staple fastener and the sheets if preferred, this result depending upon the relative positioning of the guides 7 and the staple recess.

The guides 7 are illustrated in Figs. 1 and 2 as located in front of the staple recess and movable head, and if desirable, additional guides 8 may be provided behind the staple recess to engage the corner portions of the sheets and the edges immediately adjacent to the corner portions, the guides 8 being formed integrally with or suitably attached to the base 1 and being accommodated in the opening or space that is usually present in the conventional stapling machine head when the latter is moved downwardly into contact with the anvil, and it is to be understood that the desired result can be obtained either with the guides 7, or with the guides 8, or with both sets of guides, the essential requirement being to provide instrumentalities that will enable readily positioning the sheet or sheets in predetermined relationship to the staple recess when the sheets are inserted cornerwise over the staple recess with their adjacent edges inclined to the recess.

While the sheets are held in position with adjacent edges contacting the guides 7 and 8, and the plunger 5 is depressed, the staple is secured across the corner portions of the sheets and around adjacent edges, as illustrated in Fig. 6, or as in Fig. 7 where the edges are penetrated slightly by the staple. When thus secured, the sheets are securely held against accidental displacement and if it is desired to remove the staple, this can readily be accomplished by holding the sheets with one hand, engaging the staple between the thumb and forefinger, and pulling it away from engagement with the sheets.

If it is desirable to remove a single sheet, this can easily be done by tearing the sheet along the line of the staple. This results in removing only

a small corner portion of the sheet and does not interfere with any of the usual reading matter, and does not materially deface the sheet. In some cases, if preferred, a single sheet can be removed by holding the sheets and staple in one hand while pulling the sheet to be removed away from the remaining sheets, which are still held by the frictional engagement of the staple.

In case it is desirable to provide for fastening sheets either in the manner described, or in the conventional way by penetrating the sheets, the positioning means can be arranged to be retractable out of operative position, if desired to fasten a staple in the conventional way. This is accomplished by providing guides 9 as part of a slideable plate 10 mounted on the base and movable thereover into operative position against suitable stops 11 carried by the base 1 and located so as to position the guides 9 in the predetermined relation to the staple recess. The plate 10 may be formed with a slot 12 guided on pins 13 carried by the base, and can be held against the base by spring followers 14, while 15 designates a lug or projection formed on the plate and engageable frictionally with recesses suitably arranged in the base, to hold the plate in either its operative or inoperative position.

In some instances, it is desirable to secure a sheet to the surface of a larger sheet and in spaced relation to the edges of the latter, but in such a way as to permit quick removal of the smaller sheet by arranging the staple across a corner portion thereof, and to accomplish this result, the positioning means for the sheet may be provided on the movable head instead of on the base as already described.

The head 16 may be provided with guides 17 projecting somewhat below the bottom of the movable head so as to enable positioning a sheet under the movable head and in contact with the guides 17. Each guide 17 is preferably movable vertically with relation to the head 16 in order to permit the latter to be brought down into engagement with the anvil, and this is accomplished by mounting each guide 17 on an arm 18 that is slideable vertically in a guiding chamber 19 carried by the side wall of the head, while 20 is a spring that normally holds the guide 17 down in its lowermost position for controlling positioning of the sheet.

In operation, the larger sheet is arranged in any desired position over the anvil on the base while the smaller sheet is held by the operator against the guides 17 of the movable head as the plunger is forced downwardly. This will cause the sheet immediately under the movable head to assume the proper relation to the staple and staple recess so that when fastened to the larger sheet, the staple extends around the edges of the smaller sheet and across the corner portion thereof, permitting the latter to be removed readily from the larger sheet if desired. This result can also be accomplished by fastening the guides 17 fixedly to the movable head in such position that they do not interfere with the downward movement of the head on to the anvil.

The invention is also applicable to tacking or stitching machines in which there is no anvil and the fastening element is driven into and held by a wooden or other body to which a card or sheet is to be temporarily fastened.

While the invention has been described with relation to the specific embodiment shown, it is not confined to the details herein described and illustrated, and this application is intended to

cover such modifications, changes or other adaptations as may come within the purposes of the invention and the scope of the following claims.

I claim:

1. The combination with a stapling machine for attaching superposed sheets and including a base, an anvil having a staple recess and a horizontal sheet-supporting surface acting to support a plurality of superposed sheets in horizontal position, a movable head having a staple-ejecting channel, and a plunger movable in the head to force a staple through said channel into the staple recess, of sheet-positioning means comprising guides located in a plane perpendicular to the direction of movement of the plunger and along lines at right angles to each other and inclined to said staple recess and channel, said lines being adjacent to the ends of the staple recess and channel, and said guides having engagement with adjacent edges of a sheet inserted cornerwise and edgewise into the machine in a plane generally parallel to said horizontal sheet-supporting surface with said edges inclined to the staple recess.

2. The combination with a stapling machine including a base, an anvil having a staple recess, a movable head having a staple-ejecting channel, and a plunger movable in the head to force a staple through said channel into the staple recess, of sheet-positioning means comprising guides carried by said movable head and located along lines at right angles to each other and inclined to said staple channel and recess, said lines being adjacent to the ends of said staple channel and recess when the head is in lowered position and said guides having engagement with adjacent edges of a sheet inserted cornerwise into the machine with said edges inclined to the staple channel.

3. The combination with a stapling machine including a base, an anvil having a staple recess, a movable head having a staple-ejecting channel, and a plunger movable in the head to force a staple through said channel into the staple recess, of sheet-positioning means comprising guides carried by said movable head and located symmetrically on opposite sides of the longitudinal center of the staple channel along lines at right angles to each other and inclined to the ends of said staple channel and recess

when the head is in lowered position, said guides having engagement with adjacent edges of a sheet inserted cornerwise into the machine with said edges inclined to the staple channel.

5. The combination with a staple affixing head having a staple-ejecting channel and plunger, of sheet-positioning means carried by said movable head and located along lines at right angles to each other and inclined to said staple channel, 10 said lines being adjacent to the ends of the staple channel for locating a sheet inserted cornerwise under the head.

6. The combination with a stapling machine for attaching superposed sheets and including a base, an anvil having a staple recess and a horizontal sheet-supporting surface acting to support a plurality of superposed sheets in horizontal position, a movable head having a staple-ejecting channel, and a plunger movable in the head to 20 force a staple through said channel into the staple recess, of sheet-positioning means comprising sheet-engaging devices located in a plane perpendicular to the direction of movement of the plunger on opposite sides of the longitudinal center of the staple recess, said sheet-engaging devices being arranged for engagement with adjacent edges of a sheet inserted cornerwise and edge- 25 wise into the machine in a plane generally parallel to said horizontal sheet-supporting surface 30 and acting to locate the sheet in proper position in relation to the staple recess.

7. The combination with a stapling machine for attaching superposed sheets and including a base, an anvil having a staple recess and a horizontal sheet-supporting surface acting to support a plurality of superposed sheets in horizontal position, a movable head having a staple-ejecting channel, and a plunger movable in the head to force a staple through said channel into the staple recess, of sheet-positioning means located in a plane perpendicular to the direction of movement of the plunger on opposite sides of the longitudinal center of the staple recess, said sheet-positioning means acting in relation to adjacent edges of a sheet inserted cornerwise and edgewise into the machine in a plane generally parallel to said horizontal sheet-supporting surface to indicate the proper position of the sheet in relation to the staple recess.
